RAY P. JACKSON, OF EDGEWOOD, PENNSYLVANIA, ASSIGNOR TO WESTINGHOUSE ELECTRIC AND MANUFACTURING COMPANY, A CORPORATION OF PENNSYLVANIA.

LIGHTNING-ARRESTER.

1,217,452.

Specification of Letters Patent. Patented Feb. 27, 1917.

Application filed March 28, 1913. Serial No. 757,360.

To all whom it may concern:

Be it known that I, RAY P. JACKSON, a citizen of the United States, and a resident of Edgewood, in the county of Allegheny 5 and State of Pennsylvania, have invented a new and useful Improvement in Lightning-Arresters, of which the following is a specification.

My invention relates to devices for protecting electrical circuits and electrical apparatus from injury by reason of lightning discharges, static disturbances and strains that are occasioned by the flow of high-frequency currents.

My invention relates particularly to lightning arresters of the electrostatic type wherewith apparatus in the disturbed circuit is afforded additional protection by preventing dynamo currents of large values 20 from flowing to ground in the paths of the arcs established by the discharges.

An object of my invention is to provide in a lightning arrester comprising a series of air gaps, means whereby dirt and dust 25 are prevented from accumulating and closing up the air gaps and thereby impairing the operating reliability of the arrester. I also provide a high-resistance path in series with the air gaps to limit the value of the 30 line current which may flow to ground where arcs are established by high-potential discharges.

In the accompanying drawing, the single figure is a sectional and side view of a device embodying my invention.

Referring to the drawing, the lightning arrester constructed in accordance with my invention comprises a series of superposed and spaced conducting members 1 mounted 40 upon a rod 2, a resistance rod 3 which is connected electrically in series with spark gaps 4 formed by the spaced members 1, and a connector 5 for making an electrical connection to ground. When the arrester is 45 intended for outdoor service, a rain shield 6 is added to prevent the air gaps 4 from being filled with water and thereby make paths of low conductivity. For indoor service, the rain shield may be omitted.

The members 1 are preferably in the form 50 of shallow dished sheets of non-arcing metal, such as cartridge brass, and are downwardly and outwardly flared at their lower edges. By reason of the protection afforded by 55 metallic members 1, the spark gaps 4 are

prevented from being filled with dust and dirt. The flare or the reverse curve formed at the lower edge of each member tends to cause water to flow therefrom and so does not decrease the effectiveness of the spark 60 gaps between adjacent members by lowering their conductivity. Intermediate the adjacent members 1, and serving as insulating means therefor, are porcelain washers 7. Upon the upper portion of each washer 7, is 65 formed an annular shoulder 8 which provides a seat for the metallic member 1. By this means, each metallic member 1 is insulated from, and held out of contact with the adjacent metallic members. I prefer that 70 the length of each spark gap 4 be limited between $\frac{1}{2}$ and $\frac{1}{16}$ of an inch. Felt washers 10 are inserted in the spaces between adjacent porcelain washers 7 so as to relieve them of strains and to provide against their cracking under unusual shocks.

A support 11, preferably made of brass, is secured at its upper end to the lower extremity of the rod 2. An annular flange 12 upon the support serves as a seat for the 80 bottom metallic member 1 of the series mounting it. In this manner, the bottom metallic member is connected electrically to the support 11.

The resistance rod 3, being provided at 85 each end with a copper shield 13 for insuring good electrical contact, is inclosed in an insulating and protecting tube 14. One end of the tube 14 is screwed to the lower portion of the brass support 11. To 90 the other end of the tube is secured a brass member 15 comprising a hook 16 and the connector 5, each of which is in electrical contact with the lower end of the resistance rod 3. A grounded conductor may be connected to the connector 5, thereby furnishing a discharge path over the series 95 of air gaps and through the resistance rod to ground. The purpose of the resistance rod 3 is to limit the value of the current 100 discharges, thereby protecting the generating equipment in the circuit from delivering excessive currents which will tend to flow to ground over the arcs established by the discharges. It is important, in 105 choosing the amount of the ohmic resistance of the rod 3, that it be of the proper value. If a high-resistance rod is used, the high-frequency discharge currents will 110 pass over the exterior surface of the rod in

preference to passing through the rod. This would permit excessive currents to flow from the circuit and may cause dangerous strains to be developed in the generating apparatus.

The arrester may be suspended from a pole of a transmission tower by means of a member 17 which engages the upper portion of the rod 2. Electrical connection between the arrester and a circuit conductor, which is afforded protection by the arrester, is made by means of a branch conductor 18 being screwed to a terminal 19 of the arrester. As shown in the drawing, the member 17 and the terminal 19 may be parts of a single casting. Intermediate the members 17 and a brass washer 20 is supported the rain shield 6. This type of construction connects electrically the branch conductor 18, the rain shield 6 and the top member of the series of metallic electrodes 1. When the electrical conditions of the circuit are such that a second series of air gaps and an additional resistance are required, a similar arrester may be added by suspending the same from the hook 16.

While I have herein described one embodiment of my invention, it is not intended that my invention, in all its aspects, shall be limited to this particular embodiment, as it will be apparent to anyone skilled in the art, that many changes may be made in the form of my invention without departing from the spirit thereof.

I claim as my invention:

1. A lightning arrester comprising a plurality of superposed and spaced electrodes, insulating washers interposed between adjacent electrodes, resilient cushions disposed between opposite surfaces of adjacent insulating washers, and a centrally disposed rod extending through said electrodes, insulat-

ing washers and resilient cushions in order to hold all of them in fixed relationship to one another.

45

2. A lightning arrester comprising a plurality of spaced, annular, downwardly and outwardly flared electrodes, insulating washers interposed between adjacent electrodes and provided with shoulders upon which said electrodes are seated, a centrally disposed rod projecting through openings in the electrodes and the washers, and a rain shield for the electrodes.

3. A lightning arrester comprising a plurality of spaced, annular, downwardly and outwardly flared electrodes, insulating washers interposed between adjacent electrodes, means disposed between adjacent insulating washers to absorb mechanical stresses between them, and a centrally disposed support projecting through openings in the electrodes and the insulating washers in order to hold them in fixed relationship to one another.

55

4. A lightning arrester adapted to be connected between a line conductor and ground comprising a plurality of superposed, downwardly and outwardly flared electrodes which are spaced to form spark gaps, insulating washers interposed between adjacent electrodes, a supporting rod extending through openings in the electrodes and the insulating washers in order to hold them in fixed relationship to one another, and a resistor connected in series relationship with said spark gaps.
